DESK CALENDAR

Julius J. Kaiserman, Paris, Ill., assignor to
U. O. Colson Company

Application April 7, 1955, Serial No. 499,805

7 Claims. (Cl. 40—120)

This invention relates to a desk calendar and, more particularly, to a new and improved desk calendar of the rockable type.

An object of this invention is to provide a new and improved rockable desk calendar having a weight means for balancing the calendar in an upright position.

Another object of this invention is to provide a new and improved desk calendar of the rockable type including an upwardly-extending portion adapted to carry a calendar and advertising material, a base portion having arcuate supporting means and a metal rod rigidly secured within the base portion for balancing the calendar in an upright position.

Yet another object of this invention is to provide a new and improved desk calendar of the rockable type made of plastic and embodying a metal rod to balance the calendar in an upright position and, more particularly, to provide such a calendar made in two parts which are provided with recesses and abutments for receiving the rod and which hold the rod securely in place when the parts are secured together, said parts being secured together by plastic rivets extending from one part through counter-sunk holes in the other part and upset therein.

Other objects and advantages will become apparent from the following detailed description taken in connection with the accompanying drawings, in which:

Fig. 1 is a front elevation of a desk calendar utilizing this invention;

Fig. 2 is a side elevation of the invention as shown in Fig. 1;

Fig. 3 is an exploded rear elevational view with the calendar carrying panel in a vertical plane, the back part being disconnected from the front part and rotated through 180°;

Fig. 4 is an exploded vertical sectional view taken along line 4, 5—4, 5 of Fig. 1; and

Fig. 5 is a fragmentary vertical sectional view taken along line 4, 5—4, 5 of Fig. 1.

While the invention herein described is a preferred embodiment, it is not intended to limit the invention to the specific form and arrangements shown, it being contemplated that various changes may be made by those skilled in the art without departing from the spirit and scope of the appended claims.

This invention is best shown in Figs. 1 and 2 wherein is shown a base or supporting portion 1 for the calendar and a flat panel portion 2 extending substantially upwardly therefrom. Base portion 1 is generally cylindrical so as to permit rockable movement of the calendar. A metal rod or balance weight 3 is secured within base portion 1 so as to balance the calendar in a predetermined upright position. Panel portion 2 has an outwardly opening rectangular recess 4 in approximately the lower half thereof which is adapted to receive a calendar pad 5. The calendar pad 5 has a hole punched in each upper corner so that the calendar will fit on rivets 6 extending outwardly from each upper corner of recess 4. After the calendar 5 has been positioned on rivets 6, the rivets

2

are upset, thereby securing the calendar in the recess 4. Two projections 7 extend upwardly from the base of recess 4 and are spaced from the back face of recess 4. The lower unbound edges of the calendar pad 5 are adapted to be held in a flat position by being inserted between the rear face of recess 4 and projections 7. The remaining nonrecessed portion of panel 5 is especially well adapted for displaying advertising matter.

The embodiment of the invention illustrated and described herein comprises a desk calendar made of two molded plastic parts 8 and 9, it being understood that the invention is not limited to a calendar made of a particular material, as plastic, but includes calendars made of other materials such as metal wherein a balance member is rigidly secured in a rockable calendar when two parts thereof are secured together.

In the embodiment illustrated herein the front or supporting part 8 is generally cylindrical in shape and has circular end pieces 10 integral therewith adapted to rockably support the calendar on a flat surface, as a desk. The extending panel portion 2 is integral with and extends from the supporting part 8. Two opposing lugs or abutments 11 extend longitudinally from the inner faces of circular end pieces 10. Lugs 11 are spaced so as to tightly receive therebetween balancing rod 3 to prevent endwise movement thereof. Also provided integral with supporting part 8 are three spaced cylindrically recessed brackets or projections 12. Brackets 12 are adapted to laterally receive balancing bar 3.

The clamping or rear molded plastic part 9 is generally semi-cylindrical in shape and is adapted to fit in mating engagement with supporting part 8. Extending laterally from the inner surface of rear part 9 are two cylindrically recessed brackets or projections 13 opposing brackets 12 on front part 8 and longitudinally spaced therefrom. When front part 8 and rear part 9 are secured together brackets 12 and 13 cooperate to laterally clamp balance bar 3 in a rigid position.

Front part 8 has three horizontally aligned countersunk holes 14 extending through the flat panel portion 2. Three plastic rivets 15 integral with rear or clamping part 9 extend laterally from the inner surface thereof. Rivets 15 are positioned so as to be in alignment with holes 14 when supporting part 8 and clamping part 9 are secured together. Each rivet 15 has an end portion 16 of decreased diameter which is adapted to extend through an associated hole 14 when supporting part 8 and clamping part 9 are in mating engagement. With balancing bar 3 positioned between the two plastic parts 8 and 9 in brackets 12 and 13, the end portions 16 of rivets 15 are upset in countersunk holes 14 at normal room temperature, as at 17 in Figs. 1 and 5, thus, tightly securing the two plastic parts of the calendar together.

It is believed apparent that it has been shown that applicant has developed a rockable desk calendar having a metal balancing rod rigidly secured thereto laterally and longitudinally without the use of adhesives or mechanical devices. In this calendar, the balancing rod is tightly secured between two mating parts, one of which has a series of rivets integral therewith and adapted to be upset in a series of mating countersunk holes in the other part to secure the two together. As the coefficients of expansion of both mating parts are the same, applicant has thus provided a solution to the problem of rigidly securing a metal balancing rod to a rockable calendar without the connection therebetween being adversely affected by any extreme temperatures encountered during shipment or at other times, which possibility is very likely where a metal balancing rod is directly connected to another part, especially a plastic part, as by adhesives or mechanical devices.

I claim:

1. A desk calendar comprising, in combination; a first part of plastic having a supporting portion formed to permit rocking of the calendar, and a calendar supporting portion extending upwardly therefrom, a second part of plastic secured to said first part, means for securing said two parts together, and a metal balancing rod, said first and second parts having means integral therewith for receiving and securing said metal rod therebetween in position to balance the calendar in a substantially upright position.

2. A desk calendar comprising, in combination; a plastic cylindrical supporting portion, a flat panel portion extending upwardly therefrom for carrying a calendar and providing an advertising display panel, a metal rod secured within the supporting portion for balancing the calendar in a substantially upright position, the plastic cylindrical portion being made in two substantially semi-cylindrical parts, one of which has ends integral therewith provided with opposed lugs for receiving the metal rod therebetween, said semi-cylindrical parts having opposed recessed rod clamping brackets in which said rod is mounted, the lugs and brackets acting to hold the rod tightly when said semi-cylindrical parts are secured together, and means for fastening the two parts together.

3. A desk calendar comprising, in combination; a front part having a substantially semi-cylindrical supporting portion with circular end pieces integral therewith and a flat portion extending upwardly therefrom for carrying a calendar pad, a weight balancing member, and a mating semi-cylindrical rear part having means integral therewith adapted for riveting said rear part to said front part, said front and rear parts having opposing laterally-extending recessed members adapted for rigidly clamping said weight member therebetween, the circular end pieces on said front part having opposing longitudinally-extending abutments for rigidly clamping said weight member endwise, said weight member acting to balance the calendar in a substantially upright position.

4. A desk calendar comprising, in combination; a base portion made up of two mating parts and shaped to permit rocking movement thereof, upstanding panel means for carrying a calendar extending from one of the parts, a balancing rod tightly clamped within said base portion, cooperating clamping means for said rod on said two mating parts, and means for tightly securing the two parts together.

5. A desk calendar comprising, in combination; a plastic supporting part having arcuate supporting means to permit rocking movement of the calendar, a metal balancing rod, said supporting part having opposing longitudinal lugs for tightly receiving said rod therebetween, a plastic mating part, rivets integral with said mating part for securing it to said supporting part, said supporting part and said mating part having opposing spaced recessed projections transversely extending therefrom and adapted when said supporting and mating parts are riveted together to tightly clamp said rod therebetween so as to balance the calendar in a predetermined angular position, and a generally flat portion having a recess for receiving a calendar pad and a display panel for advertising matter extending substantially upwardly from said supporting part when the calendar is in a balanced condition.

6. A desk calendar comprising, in combination; a base portion made up of two mating parts and shaped to permit rocking movement thereof, a balancing rod tightly clamped within said base portion, cooperating clamping means for said rod on said two mating parts, at least one rivet on one of the mating parts extending through an associated countersunk hole in the other mating part, said rivet being upset so as to rigidly secure the two mating parts together, and a calendar carrying portion extending upwardly from said base portion.

7. A desk calendar comprising, in combination, a base part including a first semi-cylindrical portion of plastic material having an integral end piece at each end thereof with the end pieces being provided with arcuate lower edges extending below the semi-cylindrical portion to permit rocking movement of the calendar, a calendar supporting portion extending upwardly from said first portion, said base part including a second semi-cylindrical portion of plastic material secured to the first portion, and a metal balancing rod, said first and second portions having means integral therewith for receiving and securing said metal rod therebetween, and said end pieces having means integral therewith for contacting the ends of the rod to hold the rod against endwise movement and in position to balance the calendar in a substantially upright position.
